COMPENSATING-JAW CHUCK

Harry E. Sloan, Hartford, Conn., assignor to The Cushman Chuck Company, Hartford, Conn., a corporation of Connecticut

Application April 9, 1949, Serial No. 86,577

16 Claims. (Cl. 279—119)

1

The present invention relates to improvements in chucks having movable gripping-jaws for holding work-pieces to be operated on by tools or to hold tools for performing operations on a work-piece. More particularly, the present invention relates to improvements in compensating-jaw chucks, i. e., chucks having a plurality of gripping-jaws which may be simultaneously in gripping engagement with a work-piece or the like to grip the same, despite the fact that such work-piece or the like may not be located centrally with respect to the chuck-structure or be nonsymmetrical in shape.

One of the main objects of the present invention is to provide a superior compensating-jaw chuck having a construction and arrangement of parts whereby an off-center work-piece or the like may be effectively held by a plurality of gripping-jaws without requiring independent manual adjustment of such gripping-jaws.

Another object of the present invention is to provide a superior chuck of the character referred to capable of holding an off-center or nonsymmetrical work-piece or the like without causing the binding of the elements of the chuck.

A further object of the present invention is to provide a superior compensating-jaw chuck of the general character referred to and having its jaw-operating elements constructed and arranged in a simple and compact manner and operable without a harmful degree of binding or distortion of the parts.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a face view of one form of compensating-jaw chuck constructed in accordance with the present invention;

Fig. 2 is a top or plan view thereof;

Fig. 3 is a central-longitudinal sectional view taken on the line 3—3 of Fig. 1 but on a larger scale;

Fig. 4 is a transverse sectional view taken on the line 4—4 of Fig. 3;

Fig. 5 is a longitudinal sectional view taken on the line 5—5 of Fig. 1 with certain of the parts left in elevation and showing by broken lines a nonsymmetrical work-piece being held by the gripping-jaws;

Fig. 6 is a perspective view of the actuating-head, detached;

Fig. 7 is a similar view of the mounting-ring;

Fig. 8 is a perspective view of the two parts of the compensating operating-head shown as slightly spaced from each other;

2

Fig. 9 is a perspective view of one of the compensating-members;

Fig. 10 is a similar view of one of the bell-crank levers;

Fig. 11 is a longitudinal sectional view similar to Fig. 3 but showing another form of compensating-jaw chuck constructed in accordance with the present invention;

Fig. 12 is a longitudinal sectional view similar to Fig. 5 but showing the structure of Fig. 11 as clamped upon a nonsymmetrical work-piece;

Fig. 13 is a perspective view of the reciprocating actuating-head of the chuck of Figs. 11 and 12;

15 Fig. 14 is a perspective view of the mounting-ring of the chuck of Figs. 11 and 12;

Fig. 15 is a detailed sectional view showing a modified form of compensating-member and bell-crank lever suitable for use in the chuck-structure of Figs. 11 and 12; and

20 Fig. 16 is a perspective view of the compensating-member which is shown in section in Fig. 15.

The structure of Figs. 1 to 10 inclusive

25 The compensating-jaw chuck illustrated in Figs. 1 to 10 inclusive includes a disk-like body 10 having an axial passage 11 extending therethrough from front to rear and also having a closure-plate 12 recessed into its front face.

30 In its forward portion, the body 10 is formed with three (more or less) substantially-radial guideways 13, each of which receives one of a set of three jaw-carriers 14 mounted in the said guideways with capacity for movement toward

35 and away from the central-longitudinal axis of the said body, as is common in the art of chucks. Removably secured to the front face of each of the jaw-carriers 14 is one of a set of three gripping-jaws 15 located forwardly of the front face of the body-member 10 and of the closure-plate 12.

40 The gripping-jaws 15 above referred to may be of any one of a wide variety of forms and in the present instance the said gripping-jaws are stepped to provide three inwardly-facing gripping-steps 16, 17 and 18, any one of which is adapted to be engaged with a work-piece or the like which it is desired to have the chuck grip.

45 Each of the jaw-carriers 14 above referred to is formed in its rear face with a rearwardly-opening notch 19 adapted to receive the cylindrically-contoured terminal of an arm 20 forming a rigid part of a bell-crank or coupling-member generally designated by the reference character 21. Each of the said bell-crank levers 21, in addition to its forwardly-projecting arm 20, includes also an arm 22 extending inwardly toward the longitudinal axis of the body 10 and having a cylindrically-contoured terminal as is especially well shown in Fig. 10.

Each of the bell-crank of coupling-levers 21 is accommodated in one of three similar recesses 23, one of which is located rearwardly of each of the guideways 13. Each of the said bell-crank levers 21 is mounted for turning movement upon one of three similar rods 21a which are carried by the body 10 as is especially well shown in Fig. 4.

The cylindrically-contoured terminal of each of the inwardly-extending arms 22 of the bell-crank levers 21 is received in a slot-like recess 24 extending diametrically across the outer face of the disk-like head 25 of one of three similar compensating-members, each generally designated by the reference character 26. In addition to its head 25, each compensating-member 26 is provided with an inwardly-extending threaded shank 27.

Each of the aforesaid compensating-members 26 is mounted in a two-part compensating operating-head generally designated by the reference character 28 and composed of two opposed plate-like members respectively designated by the reference characters 29 and 30, as is especially well shown in Fig. 8. The said members 29 and 30 are clamped together in any suitable manner such, for instance, as by a suitable number of screws such as 31 indicated in Fig. 3.

The operating-head 28 is formed on its outer periphery with three cylindrical recesses 32 respectively adapted to receive with a smooth turning fit the head 25 of one of the three similar compensating-members 26. Located inwardly of and communicating with each of the recesses 32 just referred to, is one of three internally-threaded sockets 33 receiving with a smooth turning fit the threaded shank of one of the said compensating-members 26.

The two-part operating-head 28 is of ring-like form and is formed internally with a spherically-contoured surface 34 engaging, with a smooth universal oscillating fit, the spherically-contoured outer surface of a mounting-ring 35.

The mounting-ring 35 above referred to is mounted upon the forwardly-projecting tubular shank 36 of a reciprocating actuating-head generally designated by the reference character 37. In addition to its tubular shank 36, the said actuating head also includes a flange-like body-portion 38 bearing and guided in the axial passage 11 in the body 10.

As before noted, the mounting-ring 35 is mounted upon the shank 36 of the actuating-head 37 and is clamped in place thereon by means of a retaining-plate 39 threadedly mounted upon the forward end of the tubular shank 36. The periphery of the retaining-plate 39 rides with a smooth sliding fit in the axial passage 11 in the body 10 and, in effect, forms part of the actuating-head 37. As will be noted by reference to Figs. 3 and 5, there is sufficient space between the forward face of the body-portion 38 and the rear face of the retaining-plate 39 to permit the two-part operating-head 28 to tilt on the mounting-ring 35, all for purposes as will more fully hereinafter appear.

Projecting rearwardly from the chuck-structure and rigidly attached to the reciprocating actuating-head 37, is an actuating-rod 40 by means of which the gripping-jaws 15 may be caused to grip a work-piece or to release the same in a manner as will more fully hereinafter appear. The actuating-rod 40 may be reciprocated for the purposes just indicated either man-

ually or by means of hydraulic, pneumatic or electrical means common in the art.

The closure-plate 12 previously referred to and which is recessed into the front face of the body 10, is provided centrally with a threaded passage 41 receiving the threaded shank 42 of a removable and replaceable conical centering-member 43 similar to a lathe-center.

As is indicated in the drawings (Figs. 3 and 5), the closure-plate 12 is notched to provide for the clearance of the jaw-carriers 14, and for the purpose of excluding dirt and chips from the interior of the chuck-structure, each of the said jaw-carriers is provided with a dirt-guard 44 which reciprocates against the front face of the closure-plate 12.

Adjacent its outer periphery, the body 10 is formed with three (more or less) passages 45 extending from front to rear therethrough and through which suitable mounting-screws (not shown) may be extended to secure the chuck-structure to a face-plate or the like of any desired machine.

The operation of the structure of Figs. 1 to 10 inclusive.

For purposes of description, let it be assumed that the reciprocating actuating-head 37 and the parts carried thereby are moved forwardly relative to the body 10 into substantially the positions in which they are indicated in Fig. 3. Under the conditions just described, the jaw-carriers 14 and hence gripping-jaws 15 will be retired outwardly preparatory to gripping a work-piece such, for instance, as the work-piece indicated by the dot-and-dash lines 46 in Fig. 5.

In instances where a work-piece such as 46 above referred to is provided in its face with a centering-recess for the reception of the point of the centering-member 43, such work-piece will be held in the desired central position for machining, grinding, or the like, by the said centering-member in the manner indicated in Fig. 5. It may further be assumed that the work-piece 46 has one or more portions of its outer surfaces nonsymmetrical, eccentric, or otherwise off-center with respect to the central-longitudinal axis of the chuck-structure and hence also with respect to the said centering-member 43.

Now when it is desired to grip a work-piece such as 46, the actuating-head 37 may be drawn rearwardly by means of the actuating-rod 40, whereupon all of the three gripping-jaws 15 will be urged inwardly.

Inasmuch as the work-piece 46 is not symmetrical with respect to the centering-member 43, one of the gripping-jaws 15 will seat against the said work-piece before either or both of the remaining two gripping-jaws seat. The full seating of all of the gripping-jaws 15 is, however, assured by the fact that the operating-head 28 may tilt on the mounting-ring 35 in the manner indicated in Fig. 5.

As the operating-head 28 tilts as above described, one or more of the compensating-members 26 will be forced to turn in the said operating-head, depending upon the degree and direction of the tilt referred to. As is indicated in Figs. 3 and 5, the compensating-members 35 do not have their heads 25 fully seated in the recesses 32 in the operating-head 28 and hence the said compensating-members are free to turn about an axis substantially perpendicular with respect to the central-longitudinal axis of the 75 chuck-structure, to thus avoid a twisting strain

being applied to the arms 22 of the bell-crank levers 21, under the circumstances above referred to.

Should it be desired to grip a work-piece by means of an inner surface thereof, the gripping-jaws 15 or their equivalent may be reversely mounted on their respective jaw-carriers 14, so that the gripping-steps 16, 17 and 18 of each of the said gripping-jaws will face outwardly.

When the chuck-structure is utilized under the circumstances just above described, the gripping-jaws 15 or their equivalent will be urged outwardly into gripping position when the reciprocating actuating-head 14 is moved forwardly, and any eccentricity or the like of the work-piece will be compensated for by the ability of the operating-head 28 to tilt on the mounting-ring 35 and the ability of the compensating-members 26 to turn, as above described.

The structure of Figs. 11 to 14 inclusive

The compensating-jaw chuck illustrated in Figs. 11 to 14 inclusive employs some of the parts and features shown in and described in connection with the structure of Figs. 1 to 10 inclusive and such corresponding parts will bear the same reference characters previously employed for the said parts and features.

Extending into the notch 19 in the rear of an adjacent jaw-carrier 14 is the cylindrically-contoured terminal of a relatively-short arm 47 forwardly projecting from a bell-crank lever or coupling-member generally designated by the reference character 48. The said bell-crank lever is one of three and corresponds to the bell-crank lever 21 previously described, save that its inwardly-extending arm 49 is slightly longer than the similar arm 22 previously described. Like the bell-crank lever 21 previously described, each of the bell-crank levers 48 is mounted for turning movement upon a rod 21a previously described.

Each of the bell-crank levers 48 above referred to is accommodated in the adjacent one of the recesses 23 in the body 10 and has the cylindrically-contoured terminal of its arm 49 extended into a slot-like recess 50 extending diametrically across the outer face of a disk-like compensating-member 51, there being a number of such compensating-members corresponding to the number of bell-crank levers 48.

Each of the aforesaid compensating-members 51 is externally threaded and is mounted with capacity for turning movement in the adjacent one of three (more or less) internally-threaded sockets 52 formed in the outer periphery of a compensating-operating-head generally designated by the reference character 53 and discharging functions substantially corresponding to the functions discharged by the operating-head 28 before described.

The operating-head 53 above referred to has a spherically-contoured exterior and is accommodated within a forwardly-opening recess or chamber 54 formed centrally within an actuating-head generally designated by the reference character 55. The said actuating-head includes a forwardly-projecting skirt 56 partly enclosing the internal recess or chamber 54 and provided in its forward portion with three clearance-notches 57 respectively registering with and providing for the clearance of the respective inwardly-extending arms 49 of the bell-crank levers 48.

The rear wall of the recess or chamber 54 in the actuating-head 55 is inclined with respect to

the central-longitudinal axis of the said actuating-head in order to provide a forwardly-facing seat 58 for engagement by the adjacent spherically-contoured outer peripheral portion of the operating-head 53, which latter has universal tilting movement with respect to the said actuating-head. The said operating-head is maintained in the engagement just referred to by means of a spherically-contoured head 59 formed at the forward end of an actuating-rod 60 extending axially through the rear portion of the actuating-head 55 and partway into the operating-head 53 as is shown in Figs. 11 and 12. The said head 59 of the actuating-rod 60 engages with a spherically-contoured seat 61 formed within the operating-head 53.

The actuating-rod 60 is held against forward movement relative to the actuating-head 55 by means of an adjusting-nut 62 threadedly mounted thereon and a lock-nut or stop-nut 63 also threadedly mounted on the said actuating-rod.

The operation of the structure of Figs. 11 to 14 inclusive

When the actuating-head 55 is moved forwardly relative to the body 10 into substantially the position indicated in Fig. 11, the operating-head 53 and the parts carried thereby will be similarly moved forwardly, with the result that the gripping-jaws 15 will be retired outwardly relative to each other and relative to the central-longitudinal axis of the structure, preparatory to gripping a desired work-piece such, for instance, as the work-piece 46 previously referred to.

Now when it is desired to grip a work-piece such, for instance, as 46, the actuating-head 55 may be forcibly drawn rearwardly by means of the actuating-rod 60, whereupon all of the gripping-jaws 15 will be urged inwardly.

Should the work-piece 46 not be symmetrical with respect to the centering-member 43, one of the gripping-jaws 15 will seat against the said work-piece before either or both of the remaining two gripping-jaws, in a manner previously described in connection with the structure of Figs. 1 to 10 inclusive. Here, again, the full seating of all of the gripping-jaws 15 is assured by the fact that the operating-head 53 may tilt within the actuating-head 55 in the manner, for instance, indicated in Fig. 12.

As the operating-head 53 tilts, as above described, one or more of the compensating-members 51 will turn in the appropriate socket or sockets 52 in the said operating-head, depending on the degree and the direction of the tilt referred to.

The structure of Figs. 11 to 14 inclusive may be utilized in various ways such, for instance, as those described in connection with the structure of Figs. 1 to 10 inclusive.

The structure of Figs. 15 and 16

In the structures previously described, the connection afforded between the bell-crank levers 21 and 48 and their respective compensating-members 26 and 51 was by means of the opposed walls of diametrical slots in the said compensating-members. In the structure of Figs. 15 and 16, the operative connection referred to is achieved in another manner as will presently be described.

Instead of employing compensating-members 51 in the operating-head 53 as has been shown and described in connection with the structure

of Figs. 12 to 14 inclusive, the said compensating-members may be replaced by slightly different but disk-like compensating-members of the type shown in Figs. 15 and 16 and generally designated by the reference character 64. The compensating-member 64 is formed in its outer face with a diametrical clearance-groove 65 across which extends a rigid cylindrical coupling-pin 66, as is especially well shown in Fig. 16.

The compensating-member 64, like the previously described members 51, is externally threaded and interfits in one of the internally-threaded sockets 52 in the operating-head 53 so as to have capacity for turning therein about an axis substantially perpendicular with respect to the central-longitudinal axis of the said operating-head 53.

Instead of providing arms with cylindrically-contoured terminals as has been the case with the structures previously described, an arm 67 (shown in Fig. 15) may be employed and which may form a part of any suitable bell-crank lever similar to the previously-described bell-crank levers 21 and 48. The inner end of the arm 67 just referred to is provided with an inwardly-opening coupling-notch 68 fitting over the coupling-pin 66 so as to permit the said arm 67 to rock with respect thereto and to provide for the turning movement of the compensating-member 64 when such turning movement is required under conditions similar to those previously described in connection with the structures of Figs. 1 to 14 inclusive.

Résumé

All of the chuck-structures previously described herein have, in common, a compensating-jaw feature whereby nonsymmetrical or off-center work-pieces may be effectively gripped without causing a cramping of the chuck mechanism, since the various compensating-members 26, 51, 64, or the like, are all mounted in a manner as will permit them to turn about an axis substantially perpendicular to the central-longitudinal axis of the chuck-structure, when such movement is required.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A compensating-jaw chuck, including in combination: a body; a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tiltable with respect to the said axis, a plurality of compensating-members carried by the said compensating operating-head and each independently oscillatable with respect thereto about an axis substantially perpendicular with respect to the central-longitudinal axis of the said body, and a plurality of coupling-members respectively operatively interconnecting one of the said oscillatable compensating-members with one of the said jaws to effect the movement of the latter when the said tiltable compensating operating-head is moved in a direction

substantially parallel with the central-longitudinal axis of the said body.

2. A compensating-jaw chuck, including in combination: a body; a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tiltable with respect to the said axis, a plurality of compensating-members threadedly connected to the said compensating operating-head and each independently oscillatable with respect thereto about an axis substantially perpendicular with respect to the central-longitudinal axis of the said body, and a plurality of coupling-members respectively operatively interconnecting one of the said oscillatable compensating-members with one of the said jaws to effect the movement of the latter when the said tiltable compensating operating-head is moved in a direction substantially parallel with the central-longitudinal axis of the said body.

3. A compensating-jaw chuck, including in combination: a body, a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tiltable with respect to the said axis, the said operating-head having a plurality of sockets in its outer periphery, a plurality of compensating-members respectively mounted in the sockets in the said compensating operating-head and each independently oscillatable in its socket and with respect to the said operating-head about an axis substantially perpendicular with respect to the central-longitudinal axis of the said body, and a plurality of coupling-members respectively operatively interconnecting one of the said oscillatable compensating-members with one of the said jaws to effect the movement of the latter when the said tiltable compensating operating-head is moved in a direction substantially parallel with the central-longitudinal axis of the said body.

4. A compensating-jaw chuck, including in combination: a body; a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tiltable with respect to the said axis, the said operating-head having a plurality of threaded sockets in its outer periphery, a plurality of threaded compensating-members respectively threaded into the sockets in the said compensating operating-head and each independently oscillatable therein about an axis substantially perpendicular with respect to the central-longitudinal axis of the said body, and a plurality of coupling-members respectively operatively interconnecting one of the said oscillatable compensating-members with one of the said jaws to effect the movement of the latter when the said tiltable compensating operating-head is moved in a direction substantially parallel with the central-longitudinal axis of the said body.

5. A compensating-jaw chuck, including in combination: a body; a plurality of jaws carried by the said body and movable with respect thereto

to toward and away from each other; and operating-means for concurrently moving the said jaws, the said operating-means including a compensating operating-head movable in substantial parallelism with the central-longitudinal axis of the said body and tilttable with respect to the said axis, a plurality of compensating-members carried by the said compensating operating-head and each independently oscillatable with respect thereto about an axis substantially perpendicular with respect to the central-longitudinal axis of the said body, each of the said compensating-members being formed in its outer surface with a recess, and a plurality of coupling-levers respectively operatively interconnecting one of said oscillatable compensating-members to one of said jaws to effect the movement of the latter when the said tilttable compensating operating-head is moved in a direction substantially parallel with the central-longitudinal axis of the said body, each of said coupling-levers having a portion extending into the recess of one of the said oscillatable compensating-members.

6. A compensating-jaw chuck, including in combination: a body; a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tilttable with respect to the said axis, a plurality of compensating-members threadedly connected to the said compensating operating-head and each independently oscillatable with respect thereto about an axis substantially perpendicular with respect to the central-longitudinal axis of the said body, each of the said compensating-members being formed in its outer surface with a recess, and a plurality of coupling-levers respectively operatively interconnecting one of said oscillatable compensating-members to one of said jaws to effect the movement of the latter when the said tilttable compensating operating-head is moved in a direction substantially parallel with the central-longitudinal axis of the said body, each of said coupling-levers having a portion extending into the recess of one of the said oscillatable compensating members.

7. A compensating-jaw chuck, including in combination: a body; a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tilttable with respect to the said axis, the said operating-head having a plurality of sockets in its outer periphery, a plurality of compensating-members respectively mounted in the sockets in the said compensating operating-head and each independently oscillatable therein about an axis substantially perpendicular with respect to the central-longitudinal axis of the said body, each of the said compensating-members being formed in its outer surface with a recess, and a plurality of coupling-levers respectively operatively interconnecting one of said oscillatable compensating-members to one of said jaws to effect the movement of the latter when the said tilttable compensating operating-head is moved in a direction substantially parallel with the central-longitudinal axis of the said body,

each of said coupling-levers having a portion extending into the recess of one of the said oscillatable compensating-members.

8. A compensating-jaw chuck, including in combination: a body; a plurality of jaws carried by the said body and movable with respect thereto toward and away from each other; and operating-means for concurrently moving the said jaws, the said operating-means including a compensating operating-head movable in substantial parallelism with the central-longitudinal axis of the said body and tilttable with respect to the said axis, the said operating-head having a plurality of threaded sockets in its outer periphery, a plurality of threaded compensating-members respectively threaded into the sockets in the said compensating operating-head and each independently oscillatable therein about an axis substantially perpendicular with respect to the central-longitudinal axis of the said body, each of the said compensating-members being formed in its outer surface with a recess, and a plurality of coupling-levers respectively operatively interconnecting one of said oscillatable compensating-members to one of said jaws to effect the movement of the latter when the said tilttable compensating operating-head is moved in a direction substantially parallel with the central-longitudinal axis of the said body, each of said coupling-levers having a portion extending into the recess of one of the said oscillatable compensating-members.

9. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body and having a seat, a compensating operating-head having a portion engaging with the said seat, the said operating-head being movable with the said actuating-head and tilttable with respect to the said seat and the said axis, a plurality of compensating-members carried by the said compensating operating-head and each independently oscillatable with respect thereto about an axis substantially perpendicular with respect to the central-longitudinal axis of the said body, and a plurality of coupling-members respectively operatively interconnecting one of the said oscillatable compensating-members with one of the said jaws to effect the movement of the latter when the said tilttable compensating operating-head is moved by the said actuating-head in a direction substantially parallel with the central-longitudinal axis of the said body.

10. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body and having a forwardly-facing seat, a compensating operating-head and having a spherically-contoured portion engaging with the said seat, the said operating-head being movable with the said actuating-head and tilttable with respect to the said seat and the said axis, a plurality of compensating-members carried by the said compensating operating-head and each independently oscillatable with respect thereto about an axis substantially perpendicular with respect to the

11

central-longitudinal axis of the said body, and a plurality of coupling-members respectively operatively interconnecting one of the said oscillatable compensating-members with one of the said jaws to effect the movement of the latter when the said tiltable compensating operating-head is moved by the said actuating-head in a direction substantially parallel with the central-longitudinal axis of the said body.

11. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body and having a chamber therein which is provided with a forwardly-facing seat, a compensating operating-head extending within the chamber in the said actuating-head and having a spherically-contoured portion engaging with the seat in the said chamber, the said operating-head being movable with the said actuating-head and tiltable with respect to the said seat and the said axis, a plurality of compensating-members carried by the said compensating operating-head and each independently oscillatable with respect thereto about an axis substantially perpendicular with respect to the central-longitudinal axis of the said body, and a plurality of coupling-members respectively operatively interconnecting one of the said oscillatable compensating-members with one of the said jaws to effect the movement of the latter when the said tiltable compensating operating-head is moved by the said actuating-head in a direction substantially parallel with the central-longitudinal axis of the said body.

12. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body and having a seat, a compensating operating-head having a plurality of threaded sockets in its outer periphery and also having a portion engaging with the said seat, the said operating-head being movable with the said actuating-head and tilttable with respect to the said seat and the said axis, a plurality of threaded compensating-members respectively in the sockets in the said compensating operating-head and each independently oscillatable therein about an axis substantially perpendicular with respect to the central-longitudinal axis of the said body, and a plurality of coupling-members respectively operatively interconnecting one of the said oscillatable compensating-members with one of the said jaws to effect the movement of the latter when the said tilttable compensating operating-head is moved by the said actuating-head in a direction substantially parallel with the central-longitudinal axis of the said body.

13. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body, a compensating operating-head articulate-

12

ly connected to the said actuating-head for movement therewith, the said operating-head being tiltable on the said actuating-head with respect to the aforesaid axis, a plurality of compensating-members carried by the said compensating operating-head and each independently oscillatable with respect thereto about an axis substantially perpendicular with respect to the central-longitudinal axis of the said body, and a plural-

10 ity of coupling-members respectively operatively interconnecting one of the said oscillatable compensating-members with one of the said jaws to effect the movement of the latter when the said 15 tiltable compensating operating-head is moved by the said actuating-head in a direction substantially parallel with the central-longitudinal axis of the said body.

14. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body and having a spherically-contoured outer peripheral portion, a compensating operating-head having a spherically-contoured inner portion engaging with the said spherically-contoured outer portion, the said operating-head being tiltable on the said actuating-head with respect to the aforesaid axis, a plurality of compensating-members carried by the said compensating operating-head and each independently oscillatable with respect thereto about an axis substantially perpendicular with respect to the central-longitudinal axis of the said body, and a plurality of coupling-members respectively operatively interconnecting one of the said oscillatable compensating-members with one of the said jaws to effect the movement of the latter when the said tiltable compensating operating-head is moved by the said actuating-head in a direction substantially parallel with the central-longitudinal axis of the said body.

47. said body.

48. 15. A compensating-jaw chuck, including in combination: a body; a plurality of jaws carried by the said body and movable with respect thereto toward and away from each other; and operating-means for concurrently moving the said jaws, the said operating-means including an actuating-head movable in substantial parallelism with the central-longitudinal axis of the said body, a compensating operating-head articulately connected to the said actuating-head for movement therewith, the said operating-head being tilttable on the said actuating-head with respect to the aforesaid axis and having a plurality of sockets in its outer periphery, a plurality of compensating-members respectively extending into the said sockets and each independently oscillatable therein about an axis substantially perpendicular with respect to the central-longitudinal axis of the said body, and a plurality of coupling-members respectively operatively interconnecting one of the said oscillatable compensating-members with one of the said jaws to effect the movement of the latter when the said tilttable compensating operating-head is moved by the said actuating-head in a direction substantially parallel with the central-longitudinal axis of the said body.

49. 50. 55. 60. 65. 70.

16. A compensating-jaw chuck, including in combination: a body; a plurality of jaws carried by the said body and movable with respect thereto.

13

to toward and away from each other; and operating-means for concurrently moving the said jaws, the said operating-means including an actuating-head movable in substantial parallelism with the central-longitudinal axis of the said body and having a spherically-contoured outer peripheral portion, a compensating operating-head having a spherically-contoured inner portion engaging with the said spherically-contoured outer portion, the said operating-head being tiltable on the said actuating-head with respect to the aforesaid axis and having a plurality of sockets in its outer periphery, a plurality of compensating-members respectively extending into the said sockets and each independently oscillatable therein about an axis substantially perpendicular with respect to the central-longitudinal axis of the said body, and a plurality of coupling-members respectively operatively interconnecting one of the said oscillatable compen-

5

sating-members with one of the said jaws to effect the movement of the latter when the said tiltable compensating operating-head is moved by the said actuating-head in a direction substantially parallel with the central-longitudinal axis of the said body.

14 HARRY E. SLOAN.
